UNITED STATES PATENT OFFICE.

PAUL L. WILSON, OF PHILADELPHIA, PENNSYLVANIA.

GLARESHIELD FOR HEADLIGHTS.

Application filed May 10, 1923. Serial No. 637,976.

To all whom it may concern:

Be it known that I, PAUL L. WILSON, a citizen of the United States, residing at Philadelphia, in the county of Philadelphia and 5 State of Pennsylvania, have invented certain new and useful Improvements in Glare-shields for Headlights, of which the following is a specification.

My invention relates to glare shields for 10 headlights and its object is to provide a shield which will obstruct the glare of a headlight in an upward and a horizontal direction and permit the light to pass downward to the road, and which will be of simple and durable construction.

This object, and other advantageous ends 15 which will be described hereinafter, I attain in the following manner, reference being had to the accompanying drawings in 20 which—

Figure 1 is a central section through a headlight having my invention applied thereto,

Figure 2 a section on line 2—2 of Figure 1, 25 Figure 3 an enlarged fragmentary central section similar to Figure 1 showing a modified form of securing means,

Figure 4 a view similar to Figure 3 showing another form of securing means, and 30

Figure 5 a perspective view of the inclined shielding plates which form a part of my invention.

Referring to the drawings, 1 indicates a casing of a headlight, 2 the lamp, 3 the reflector, 4 the lens and 5 the rim for securing the lens to the reflector.

My invention includes a band 6 provided with lugs 7 radiating therefrom adapted to be placed between the lens and rim of the 40 headlight and securely held therebetween. Inclined shielding plates 8 are spaced within the band and secured thereto by any suitable means. The inclination and width of the strip are such that the outer edge 9 of each plate and the inner edge 10 of the lower adjacent plate will intersect a horizontal plane as indicated in dot-and-dash lines at 11 in Figure 1. This arrangement of the plates prevents the light from passing in an upward and a horizontal direction but permits the rays to pass downward to illuminate the road. The shielding plates are

50 preferably constructed from a strip of metal by cutting notches 12 therein and bending the strips at the notches as shown at 13 in Figure 5. The shielding plates in this bent

form are then placed within the band and held therein by frictional engagement therewith. The shielding plates may be soldered to the band or dipped into a molten mass of 60 low temperature, such as lead, tin, zinc or the like to securely hold the plates to the band.

In Figure 3 I have shown a form of securing means which includes lugs 14 bent upward from the band and secured to the rim 65 5 by screws 15.

In Figure 4 I have shown a form of securing means which includes strip springs 16 secured to the band 6 by rivets 17. The 70 springs embrace the rim and casing and hold the glare shield in position. In all other respects the construction in Figures 3 and 4 is similar to that shown in Figures 1, 2 and 5 and I have therefore given corresponding parts similar reference characters.

To apply my improved glare shield to a headlight, the rim 5 is removed from the headlight and the glare shield placed within the opening of the rim so that the radiating parts or lugs 7 will be within the rim. The lens is placed against the glare shield within the rim and the rim put on the headlight in the usual manner.

By providing a glare shield having the 85 shielding plates of such a width and disposed at an incline so that the outer edge of each plate and the inner edge of the lower adjacent plate will intersect a horizontal plane, the glare from the headlight is obstructed to an observer above a horizontal plane with the headlight while in a downward direction toward the road, the light passes freely between the plates practically unobstructed, thus illuminating the road in 90 the usual manner. By making the shielding plates comparatively wide so that they will project beyond the band 6, the road may be illuminated a considerable distance from the headlight without throwing the glare to 100 an observer at that distance.

If desired, a flange may be provided around the band instead of the lugs for securing purposes, but I have found that the lugs make a lighter structure and serve as 105 well.

While I have described my invention as taking a particular form, it will be understood that the various parts of my invention may be changed without departing 110 from the spirit thereof, and hence I do not limit myself to the precise construction set

forth, but consider that I am at liberty to make such changes and alterations as fairly come within the scope of the appended claim.

Having thus described my invention, 5 what I claim as new and desire to secure by Letters Patent is:—

A glare shield for headlights including a band; a strip of metal bent to form inclined shielding plates within the band and having their inner edges flush with the inner edge of the band and their entire outer edges 10 projecting equal distances beyond the outer edge of the band, the outer edge of each

plate and the inner edge of the lower adjacent plate intersecting a horizontal plane, 15 and means for securing the band to the headlight whereby the inner edges of the plates will abut the lens of the headlight.

In testimony whereof I have signed my name to this specification in the presence of 20 two subscribing witnesses.

PAUL L. WILSON.
